UNITED STATES PATENT OFFICE.

JAMES HAY HUTCHISON, OF LONDON, ENGLAND.

DESIGN FOR A FONT OF PRINTING-TYPE.

SPECIFICATION forming part of Design No. 31,216, dated July 11, 1899.

Application filed June 9, 1899. Serial No. 719,976. Term of patent 14 years.

To all whom it may concern:

Be it known that I, JAMES HAY HUTCHISON, a subject of Her Majesty the Queen of Great Britain, and a resident of London, in the county of Middlesex, England, have invented and produced a certain new and original Design for a Font of Printing-Type, of which the following is a full, clear, and exact specification, reference being had to the accompanying drawing, forming a part thereof.

I have illustrated my invention in the accompanying drawing, in which I have shown a plan view of a complete set of type—upper and lower case and numerals.

The leading or material feature of my design consists of the form of characters which

present to the eye a new and attractive appearance; and my invention relates to the configuration or design of the type-faces, the same being the usual characters that go to make up a font of type.

Having described my invention, what I claim as new, and desire to secure by Letters Patent, is—

The design for a font of printing-type, substantially as described and shown.

Signed, at 120 Salisbury Square, in the city of London, this 31st day of May, 1899.

JAMES HAY HUTCHISON.
